UNITED STATES PATENT OFFICE.

ANDREW BROWN McLAREN, OF TORONTO, ONTARIO, CANADA.

GUMMING MACHINE.

Application filed August 12, 1921. Serial No. 491,757.

To all whom it may concern:

Be it known that I, ANDREW BROWN McLAREN, a subject of the King of Great Britain, residing at the city of Toronto, in the 5 county of York and Province of Ontario, Dominion of Canada, have invented new and useful Improvements in Gummimg Machines, of which the following is a specification.

10 My invention relates to a gumming machine in which liquid glue or other paste is distributed by a roller suitably journaled in the machine, in combination with the necessary operating mechanism, and arranged in 15 longitudinal relation with a reservoir or trough suitably supported and adapted to be actuated by foot or hand power, to regulate and supply the liquid glue or paste to the periphery of the roller as it turns either 20 continuously or intermittently accordingly with the class or amount of work passing through the machine and at the discretion of the operator.

I make no especial claim to the operating 25 mechanism, other than the combination and functional features of the reservoir or glue trough, which is the main object of my invention, the essential object being to provide against churning, foaming and the over- 30 flow of the glue caused by agitation resulting from the turning of the distributing roller, which closes one side of the reservoir, and to prevent any agitation the distributing roller is separated from the main volume of the 35 glue by an adjusting and regulating gate positioned in the reservoir in close proximity and in parallel relation with the periphery of the roller.

In the accompanying drawings:—

40 Figure 1 is a sectional elevational view of the machine; and

Figure 2 is a detail sectional view of the reservoir.

Similar letters of reference refer to similar 45 parts throughout the specification and drawings.

a designates one side of the main frame of the machine, in which the various operating parts are suitably journaled and set.

50 I make no claim to the shape or nature of the frame, as my device is especially adapted to be used in connection with any of the various classes of gumming machines.

b is a gum distributing roller which is 55 suitably journaled crosswise in the main frame of the machine, and *c* is a canvas

carrier on which the glued materials are carried away from the distributing roller *b*. The canvas carrier *c* consists of an endless canvas belt passing over rollers, one of 60 the rollers *d* being journaled in the main frame *a* in parallel and close proximity with the distributing roller *b*, the other roller (not shown) is supported and journaled in a frame situated at some distance from the 65 machine.

e and *f* designate a pair of rollers suitably journaled in the main frame of the machine slightly forward and in parallel relation with the distributing roller *b*, at 70 the inner end of the work table *g*, supported on the front end of the main frame, and from which the material to be gummed is passed to the guide rollers *e* and *f*, to be directed to the periphery of the distributing 75 roller *b*, and by which the gum is equally distributed, and carried to engage with a series of picker fingers *h*, pivotally carried on a rod *i* extending across the machine.

The gummed material adhering to the 80 periphery of the distributing roller *b* as the roller turns, carries it until it contacts with the fingers *h*, by which it is picked off and caused to deposit on the canvas carrier, and conveyed to where the operators may remove 85 it to the various uses and purposes for which the gum is applied.

All of the rollers *b*, *d*, *e* and *f* are suitably journaled and arranged to be actuated by mechanism forming part of the machine, 90 which are not shown or described, as they do not form any essential feature of my device, other than in the general modus operandi.

Set in the upper part of the main frame 95 juxtaposition with the periphery of the distributing roller *b*, is a reservoir or trough *j* adapted to contain the liquid glue or gum, from which it is distributed to the roller *b* as it revolves, either intermittently or continuously, accordingly with the option of the operator, and the class and amount of the work passing through the machine.

The reservoir or trough *j* is formed with a bottom declining towards the roller *b*. In 105 normal position the back edge of the bottom engages in frictional contact with the face of the roller *b*. The reservoir or trough *j* is supported in the main frame *a* of the machine by a link *k*, by which it is adapted to be actuated either towards or away from the face of the roller *b*, by a hand wheel *l*, for 110

the purpose of regulating the amount of glue or gum to be fed to the face of the roller, as it revolves.

Set across the back end of the reservoir 5 or trough *j* is a gate *m* adapted to vertical adjustment to further regulate the amount of glue or gum passing from the main portion of the reservoir under the gate to feed to the face of the roller, but secondly and 10 especially to prevent the roller from directly contacting and turning with the main volume of the glue, to eliminate all chance of the roller from churning, foaming and overflowing the glue over the sides and ends 15 of the reservoir or trough, especially as it is found from experience that glue or gum loses its adhesiveness, when it becomes churned and foamed.

Hinged to the top face of the gate *m* is 20 a scraper *n*, adapted to engage in tangential relation with the roller *b* to gather and direct back into the reservoir or trough *j* any superfluous glue or gum undistributed from the roller, onto the materials passing 25 through the machine. The scraper *n* is hinged to the top face of the gate, by any form of spring hinge *o*, so that it may be adjusted backwardly as shown in dotted lines, when the machine is out of operation, 30 so as not to stick to the face of the roller and to facilitate in cleaning the parts.

The gate *m* is held in adjustable relation with the reservoir or trough *j* by a lever rod *p*, pivotally supported to the front end of 35 the reservoir by a bracket *q* and connected with the gate by a vertically extending arm *r*.

s designates a foot lever pivotally connected with the main frame, and *t* is a 40 connecting rod extending between the foot lever and a crank arm *u* set in the side of the frame *a*, and pivotally connected with a link *v*, attached with the front end of the lever rod *p*. By a downward pressure on 45 the foot lever *s* the lever rod *p* is tripped, by which the gate may be vertically adjusted, to open a slight interval between the lower edge of the gate and the bottom of the reservoir, to allow for a sufficient flow of

the glue or gum to pass from the reservoir, 50 to be taken up by the roller *b* as it revolves, and in turn distribute it equally to the paper or other materials directed through the guide rollers *e* and *f* from the feed table *g*.

The foot lever may be suitably connected 55 up with the starting and stopping mechanism of the machine, by which all of the operating parts may be arranged to operate in unison or otherwise, these features are apart from the essential features of my device, which lies in the gate or baffle, arranged in combination with the reservoir or trough. Various modifications may be made in the 60 shape and means for actuating the gate without deviating from the nature of my 65 invention.

What I claim as new and desire to secure by Letters Patent is:—

A glueing machine, in combination with the gum reservoir thereof, said gum reservoir consisting of a metal trough formed with a declining bottom, said reservoir located in parallel and juxtaposition with the distributing roller forming an essential part thereof, an adjustable gate fitted across the 75 back end of the said reservoir, a scraper connected in hinged relation across the top of said gate, said scraper adapted to engage in tangential relation against the periphery of the said distributing roller, a foot lever 80 arranged in conjunction with the said gate and said reservoir, said gate adapted to be vertically adjusted by the said foot lever for the purpose of permitting a determined quantity of glue to escape from the said 85 reservoir onto the periphery of the said distributing roller, the said scraper adapted to gather and direct back into the said reservoir the superfluous glue from the face of the said roller, substantially as specified. 90

Signed at Toronto, this 25th day of July, 1921, in the presence of the undersigned witnesses.

ANDREW BROWN McLAREN.
